UNITED STATES PATENT OFFICE.

MAXIMILIEN KOTYRA, OF PARIS, FRANCE.

KEYBOARD TELEGRAPHIC TRANSMITTER.

SPECIFICATION forming part of Letters Patent No. 779,223, dated January 3, 1905.

Application filed March 21, 1904. Serial No. 199,280.

To all whom it may concern:

Be it known that I, MAXIMILIEN KOTYRA, electrical engineer, a citizen of the Republic of France, residing at 26 Avenue des Ternes,

5 Paris, France, (post-office address,) have invented a new and useful Improvement in Keyboard Telegraphic Transmitters, (for which Letters Patent have been applied for in France under date of July 1, 1903, No. 333,498; in 10 Germany under date of July 4, 1903, not issued; in England under date of July 7, 1903, No. 15,065, and in Belgium under date of January 22, 1904, not issued, of which the following is a specification.

15 This invention relates to keyboard-transmitters adapted to facilitate, simplify, and accelerate in a considerable degree the transmission of telegrams by means of telegraphic apparatus which utilizes an alphabet, such as 20 the Morse alphabet, in which a particular combination of dots and dashes represents conventionally each letter or symbol.

This invention has for its object to enable even an inexperienced person to transmit a 25 telegram mechanically with the aid of the Morse alphabet or other similar alphabet without having to execute any preliminary manipulation and in a very simple, rapid, and sure manner by merely touching the keys of a keyboard each key of which corresponds to a sign 30 of the alphabet that is adopted, thereby relieving the operator of all enervating and tiring muscular effort, and so that the operator has merely to depress the key, which opposes 35 only an insignificant resistance to his finger. All the other mechanical work necessitated by the transmission of the corresponding signal is then effected immediately and automatically by the action of a motor in continual 40 motion in such a manner that the depression of each key has the immediate and direct result of throwing into operation the mechanism for transmitting the corresponding signal.

In the accompanying drawings, which illustrate, by way of example, one of the ways in 45 which this invention may be carried out, Figure 1 is a side elevation, with the framing of the keyboard shown in section, of the transmitting mechanism corresponding to one of 50 the keys. It is to be understood that the mech-

anism of all the other keys, which are equal in number to that of the signals, letters, and symbols to be transmitted, are identical to that shown. Fig. 1 shows the key in its normal position of rest ready to be depressed for the purpose of transmitting a signal. Fig. 2 is a similar view showing the key depressed and with the parts in their respective positions for transmitting the signal. Fig. 3 is a similar view showing the parts at the moment at which the transmission of the signal has just been completed and the automatic disconnection is about to be effected and the key is about to rise and move forward again. Fig. 4 is a section on the line 4 4 of Fig. 1. Fig. 5 is a section on 65 the line 5 5 of Fig. 2. Fig. 6 is a section on the line 6 6 of Fig. 2. Fig. 7 is a section on the line 7 7 of Fig. 2. Fig. 8 is a perspective view of a portion of the plate or bar carrying the groups of fixed contacts.

The framing of the apparatus is shown as having the shape of a rectangular box composed of a body *a* and a cover *b*, hinged together at *c*. A shaft *d* carries a long pinion *d'*, which extends over the entire length of 75 the box and is set in motion in a continuous manner by a suitable motor. (Not shown.) The shaft *d* rotates in bearings (not shown) situated at the two ends of the box in front and near the lower part of the latter. Near 80 the pinion *d'* and slightly behind it there is fixed at the two ends of the box a contact bar or plate *e*, on the face of which are formed side by side groups *e' e''*, &c., Fig. 8, of projecting parts and depressions, the particular 85 arrangement of which in each group corresponds to the particular combination of dots and dashes selected to reproduce one of the letters or symbols of the alphabet employed. Above each of these groups of contacts there 90 is arranged one of the automatic transmitting mechanisms brought into action by the operation of the circuit-closing keys, only one of which is shown in the drawings. Each of these mechanisms consists of a circuit-closing 95 key provided with a stem *f*, pivoted at *f'* in a slide-block *g*, which is guided by a rod *g'*, and screws *g''* in a tubular guide *g''*, and a slideway *g''*, fixed to the framing. The slide-block *g* is normally drawn forward into the 100

position shown in Fig. 1 by a spring h , and the key f is normally kept raised in the horizontal position (shown in Fig. 1) by a flat spring i , fixed by one of its ends to the slide-block g and acting at the other end upon a pin f^2 , provided in the side of the key f .

On the under side of the stem f there is formed a rack j , adapted to engage with the pinion d' when the rack is depressed. The stem f of the key may be of round or any other suitable cross-section, and it is made thinner or recessed at two points, k and m , in its length, corresponding with the two ends of its stroke, Fig. 1 and Fig. 3. The stem f of the key passes through the front of the box or framing by means of a slot n in the form of a "dumb-bell"—that is to say, it is formed with an enlarged portion at its two ends in which the round body of the stem f can pass and with a contracted or throttled intermediate portion in which only the thin portions k and m of the said stem can pass.

It should be understood that I do not limit myself to the slot n being formed in the outside casing, as it may readily be formed in a separate piece or lug without departing from the spirit and scope of my invention.

Below the stem f of the circuit-closing key there is also fixed near its end, where the pivot f' is situated, a shoe or block o , carrying one or more contact-springs p , arranged in such a manner as to come in elastic contact with the corresponding group of contacts $e^1 e^2$ of the bar e when the key is depressed. A set-screw p' , screwed into the block o , prevents the spring from entering too far forward into the depressions of the said group of contacts when the spring is caused to bear on the top of the said group, as hereinafter described.

The spring p may be electrically connected through the apparatus to the battery, and the plate or bar e , which is insulated from the apparatus by suitable means, may be connected to the line, or vice versa.

The several parts being arranged as hereinbefore described, the mode of operation is as follows: When it is desired to transmit a particular letter or symbol of the alphabet, the operator has merely to depress the corresponding key to the bottom of its stroke. This he is able to do, because up to this moment the thin portion k of the stem f of the circuit-closing key is situated coincident with the slot n . This causes the rack j to engage with the pinion d' , which is being continuously rotated by the action of a motor (not shown) in the sense of the arrow x . As soon as this engagement is effected the key is drawn back by the pinion acting on the rack, so that the round portion of the stem f passes at once into the lower enlarged portion of the slot n , whereby the key is prevented from rising again. This key continues to be drawn backward by the pinion, so that the contact

spring or springs p , which have moved down with the said key, now rub upon the projecting portions of the corresponding group of contacts—for instance, the group e^1 , Fig. 2. Each time the spring p rubs over one of the projecting contacts of the group the battery is thereby connected temporarily to the line and sends along the line a long or short impulse, according to the length of the face of the projection over which the spring is passing at the time, so that, as will be readily understood from the explanations given hereinbefore, the receiving instrument will receive a succession of dashes and dots representing in combination the letter or symbol that corresponds to the key which has been depressed. As soon as the stem f reaches the end of its backward travel and the signal has been completely transmitted the thin portion m of the stem f comes in line with the slot n , Fig. 3. The stem f is then immediately raised by its spring i , whereby the rack j becomes disengaged from the pinion d' , and as soon as the stem f has moved back into the upper enlarged portion of the slot n the key and its appurtenant parts are moved forward again by the spring h into the position shown in Fig. 1, ready for the transmission of a fresh signal.

It is to be noted that in addition to the hereinbefore-stated advantages this invention affords also the advantage of dispensing with insulating portions between the long and short conducting portions of the groups $e^1 e^2$ of contacts of the bar e representing the letters and symbols of the alphabet employed. This obviates the drawbacks which in other systems may result from the metallization of the insulating-surfaces due to the repeated rubbing of the rubbing contacts, such as p . It is further to be clearly understood that this invention is not strictly limited to the precise details shown and described herein. It is obvious that the respective forms, dimensions, and arrangements of the several parts constituting the apparatus may be varied without departing from the nature of this invention.

What I claim as my invention, and desire to secure by Letters Patent of the United States, is—

1. In a telegraphic transmitter of the class described, the combination with a suitable member provided with a slot of substantially dumb-bell form, of a circuit-closing member having a stem passing through said slot conforming in cross-section to the enlarged portion thereof and provided with a thinned portion constructed to pass through the contracted portion of said slot, substantially as described.

2. In a telegraphic transmitter of the class described, the combination with a suitable member provided with a slot of substantially dumb-bell form, of a circuit-closing member having a stem passing through said slot con-

forming in cross-section to the enlarged portion thereof and provided with a thinned portion constructed to pass through the contracted portion of said slot, and means for maintaining said stem in the upper portion of said slot, substantially as described.

- 5 3. In a telegraphic transmitter of the class described, the combination with a suitable casing provided with a slot of substantially 35 dumb-bell form, of a circuit-closing member constructed to have a sliding movement within said casing, having a stem passing through said slot conforming in cross-section to the enlarged portion thereof, and provided at two 40 15 points in its length corresponding respectively to the two ends of its travel with thinned portions constructed to pass through the contracted portion of said slot, substantially as described.
- 20 4. In a telegraphic transmitter of the class described, the combination with a suitable member provided with a slot of substantially dumb-bell form, of a circuit-closing member having a spring-pressed stem passing through 45 25 said slot conforming in cross-section to the enlarged portion thereof, and normally maintained in the upper portion, and provided with a thinned portion constructed to pass through the contracted portion of said slot, substantially as described.
- 30 5. In a telegraphic transmitter of the class

described, the combination with a suitable member provided with a slot of substantially dumb-bell form, of a circuit-closing member comprising a sliding block, a stem pivoted thereto passing through said slot and conforming in cross-section to the enlarged portion thereof, means for maintaining said stem in the upper portion of said slot and a thinned portion on said stem constructed to pass 40 through the contracted portion of said slot, substantially as described.

6. In a telegraphic transmitter of the class described, the combination with a suitable casing provided with a slot of substantially 45 dumb-bell form, of a circuit-closing member having a stem passing through said slot conforming in cross-section to the enlarged portion thereof and provided with a thinned portion constructed to pass through the contracted portion of said slot, a signal - producer, means for actuating said circuit-closer over said signal-producer and means for returning said circuit-closer to normal position, substantially as described.

55 In testimony whereof I have signed my name to this specification in the presence of two subscribing witnesses.

MAXIMILIEN KOTYRA.
